US0D1064169S

(12) **United States Design Patent** (10) **Patent No.:** **US D1,064,169 S**
(45) **Date of Patent:** **** Feb. 25, 2025**

(54) **SELF-DEFENSE PEPPER SPRAY ASSEMBLY**

(71) Applicant: **Bestie Defense LLC**, Pacific Palisades, CA (US)

(72) Inventors: **Sarah Katherine Haspel**, Pacific Palisades, CA (US); **Norman Allen Tolentino**, Westminster, CA (US)

(73) Assignee: **Bestie Defense, LLC**, Los Angeles, CA (US)

(**) Term: **15 Years**

(21) Appl. No.: **29/972,102**

(22) Filed: **Nov. 7, 2024**

(51) **LOC (15) Cl.** 22-02

(52) **U.S. Cl.**

USPC **D22/117**

(58) **Field of Classification Search**

USPC D22/117; D26/37, 38

CPC B65D 83/206; F41H 9/10

(57) **CLAIM**

The ornamental design for self-defense pepper spray assembly, as shown and described.

DESCRIPTION

FIG. 1 is a rear perspective view a first embodiment of our self-defense pepper spray assembly, showing the new design;

FIG. 2 is rear elevation view thereof;

FIG. 3 is front elevation view thereof;

FIG. 4 is a left side elevation view thereof, a right side elevation being a mirror image thereof;

FIG. 5 is a top plan view thereof;

FIG. 6 is a bottom plan view thereof;

FIG. 7 is a rear perspective view a second embodiment of our self-defense pepper spray assembly, showing the new design;

FIG. 8 is rear elevation view thereof;

FIG. 9 is front elevation view thereof;

FIG. 10 is a left side elevation view thereof, a right side elevation being a mirror image thereof;

FIG. 11 is a top plan view thereof; and,

FIG. 12 is a bottom plan view thereof.

The broken lines shown in FIG. 12 depict unclaimed portions of the self-defense pepper spray assembly only, and form no part of the claimed design.

1 Claim, 8 Drawing Sheets
